OR D 12,768

Design No. 12,768, dated February 14, 1892.

UNITED STATES PATENT OFFICE.

GEORGE G. THOMAS, OF PHILADELPHIA, PENNSYLVANIA.

DESIGN FOR A HEATING-STOVE.

SPECIFICATION forming part of Design No. 12,768, dated February 14, 1882.

Application filed January 13, 1882. Term of patent 7 years.

To all whom it may concern:

Be it known that I, GEORGE G. THOMAS, a citizen of the United States, residing at Philadelphia, Pennsylvania, have invented or produced a new and original Design for a Heating-Stove, of which the following is a specification.

My design for a heating-stove is fully shown in the accompanying photographic illustration.

The design comprises the base or ash-pit section A, tile band B, illuminating-section D, and upper section, E. The general shape of the stove is rectangular.

The base A has in front a pair of doors, a, and on each end an open-work panel, b, and closed panel d.

The tile band B is of a character too fully shown to need detailed description, and in front of the same is a fender-rail, e.

The illuminating-section D comprises two parts, f and g. The part f has a vertical front, i, and vertical ends m, and the part g has vertical ends n and an inclined front, p.

The design for the front i comprises essentially a pair of doors, k', in imitation of the doors of a cabinet, and each consisting of a border or frame, k, inclosing a series of small panes of mica.

The design for the ends m comprises an outer border, a solid panel, h, and an illuminating-panel, h', with small mica panes.

The design for the ends n comprises the vertical band s, oblong door s', and triangular panel s², and the design for the front p comprises an oblong rectangular frame, t, inclosing a series of small mica panes, t'.

The design for the upper section, E, comprises a tile band, w, surmounted by an inclined

40 top, w', with rail x.

I claim—

1. The design for the base-section A, said design comprising the front doors, a, and the open-work panels b and closed panels d at the ends, as shown and described. 45

2. The design comprising the base-section A, illuminating-section D, and intervening tile band, B, as shown and described.

3. The design for the illuminating-section D, said design comprising the vertical body f and contracted or inclined top g, both having mica panes, as shown and described. 50

4. The design for the front i, said design comprising a pair of doors, k', each having a rectangular border, k, inclosing small mica panes, as shown and described. 55

5. The design for the ends m, said design comprising the solid panel h and the illuminating-panel h', with small mica panes, as shown and described. 60

6. The design for the inclined front p, said design comprising the oblong rectangular frame t, with small mica panes t', as shown and described.

7. The design for the ends n, said design comprising the upright band s, oblong door s', and triangular panel s², as shown and described. 65

8. The design for the upper section, E, said design comprising the tile band w and inclined top w', as shown and described. 70

9. The design for the complete stove, said design comprising the base-section A, tile band B, illuminating-section D, and upper section, E, as shown and described. 75

In testimony whereof I have signed my name to this specification in the presence of two subscribing witnesses.

GEO. G. THOMAS.
